UNITED STATES PATENT OFFICE.

BURT NEULON PIERCE, OF FLINT, MICHIGAN.

CARBURETER.

1,194,876.

Specification of Letters Patent. Patented Aug. 15, 1916.

Application filed April 21, 1915, Serial No. 22,839. Renewed January 26, 1916. Serial No. 74,478.

To all whom it may concern:

Be it known that I, BURT NEULON PIERCE, a citizen of the United States, residing at Flint, in the county of Genesee and State of Michigan, have invented certain new and useful Improvements in Carbureters, of which the following is a specification, reference being had therein to the accompanying drawing.

10 This invention relates to certain new and useful improvements in carbureters and is an improvement upon a construction of carbureter as disclosed in my application filed February 19, 1915, Serial Number 9324; the 15 object being to provide means for adjusting the position of the floating valve in the auxiliary air chamber so as to allow a large volume of air to pass into the carbureter through the auxiliary air inlets to decrease 20 the suction in order to prevent gas from being drawn into the carbureter when coasting down a hill and the motor is being used as a brake.

Another object of my invention is to provide 25 a spring support for the floating valve which normally floats the same in order to hold the floating valve slightly raised so as to allow an additional volume of air to enter the carbureter in order to regulate the idling 30 of the motor or to allow a greater volume of air to enter the mixing chamber to decrease the mixture in order to obtain a greater mileage.

Another object of the invention is to provide 35 means for regulating the floating valve which is manually controlled from the dash in order that the floating valve can be adjusted into various positions in respect to its seat.

40 Other and further objects and advantages of the invention will be hereinafter set forth and the novel features thereof defined by the appended claims.

In the drawings—Figure 1, is a perspective 45 of my improved construction of carbureter; Fig. 2, is a longitudinal vertical section through the same; Fig. 3, is a perspective of the yoke and its operating means, showing the spring for supporting the floating 50 valve in position thereon; Fig. 4, is a section through the yoke and cam as shown in Fig. 3, showing the yoke in full lines in lowered position and in dotted lines in in-

termediate and high positions so as to adjust the floating valve through the medium 55 of the spring support, into various positions; and Fig. 5, is a perspective of the pivoted fork and crank shaft showing the means for retarding the oscillation of the crank shaft.

60 Like numerals of reference refer to like parts in the several figures of the drawings.

In the drawings, 1 indicates the bowl of a carbureter which is provided with the usual float and fuel supply chamber. A central 65 tubular member 2 is mounted within the bowl, forming a central air duct to which is connected an air supply pipe 3 said air duct having a main fuel valve control nozzle 4 extending into a Venturi tube 5 mounted 70 within the air duct, said Venturi tube projecting upwardly beyond the tubular member 2. Arranged over the bowl above the flange of the tubular member, is a casing 6 forming an auxiliary air chamber 7 having 75 oppositely disposed air inlets 8, and mounted on top of the casing 6 is a casing 9 provided with a mixing chamber 10 at its lower end into which the upper end of the Venturi tube extends and a throttle chamber 10' at 80 its upper end having the usual pivoted throttle valve mounted therein, said casing being provided with a heating chamber.

85 A high speed nozzle 12 is arranged within the auxiliary air chamber and is carried by a tube which extends down into the bowl through which fuel is adapted to be sucked when the engine is traveling at a high rate of speed in order to increase the richness of the mixture.

90 The top of the auxiliary air chamber 6, is provided with a conical valve seat 13 in which is adapted to be seated, the conical marginal edge of a floating valve 15 which is provided with a bearing sleeve 16 slidably 95 mounted upon the upper end portion of a Venturi tube, as clearly shown in Fig. 2. A fork 17 is mounted on a shaft arranged within the mixing chamber and is normally held in a plane slightly above the floating 100 valve so that when the valve is raised, a resistance is exerted against the upward movement of the floating valve through the medium of a weight carried by an arm secured upon said shaft so as to retard the 105 opening movement thereof.

The construction so far described, is substantially the same as disclosed in my application, Serial Number 9324, filed February 19, 1915, with the exception of the floating valve, which is formed slightly heavier for the purpose hereinafter fully described.

- My improvement upon the construction so far described, is the provision of means for adjusting the position of the floating valve 10 in respect to its seat and comprises a pivoted yoke 18 mounted within a recess formed in the wall of the auxiliary air chamber and provided with a curved portion 19 which is adapted to be engaged by a cam 20 mounted 15 on a shaft 21 extending outwardly beyond the casing as shown in Fig. 1, said shaft having a crank arm 2 fixed thereon to the free end of which is connected an operating rod 23 which is adapted to extend to the 20 dash of the motor vehicle to which the carbureter is attached so that the shaft 21 can be rocked in order to shift the position of the cam 20 so as to adjust the position of the yoke 18.
- 25 The under side of the floating valve is provided with an annular recess to receive the upper portion of a coil spring 24 which is carried by a flanged collar 25 mounted upon the arms of the yoke 18, as clearly shown in 30 Figs. 2 and 3, whereby by operating the rod 23, the yoke can be adjusted into any of the positions shown in Fig. 4, so as to adjust the position of the floating valve in respect to its seat.
- 35 When the cam on the shaft 21, is in the position shown in Figs. 2 and 3, the yoke is in lowered position so as to allow the floating valve to drop tightly onto its seat so as to cut off the auxiliary air supply in order to 40 increase the suction within the Venturi tube whereby the richness of the mixture will be increased so that the motor to which the carbureter is attached can be readily started in cold weather or when the motor is cold.
- 45 By shifting the cam through the medium of the shaft and operating rod into central position, the yoke is raised to such an extent that the floating valve is raised off of its seat approximately five-sixteenths of an inch 50 ($\frac{5}{16}$ ") which allows such a volume of air to pass through the auxiliary air chamber into the mixing chamber through the air inlet ports thereof, that the suction is decreased to such an extent that air will not enter 55 through the Venturi tube and the motor can be used for braking the vehicle without wasting fuel. By oscillating the shaft carrying the cam so as to move the cam over to the other side of the shaft, the yoke 18 will be 60 thrown into intermediate position so as to slightly float the floating valve and regulate the idling of the motor; an adjustable stop 65 being employed which is adapted to cooperate with the crank 22 so as to limit the movement of the cam in respect to the por-

tion 19 of the yoke 18 whereby the position of the yoke can be readily adjusted so as to adjust the relative position of the floating valve in respect to its seat. By adjusting the floating valve in this manner, the richness of 70 the mixture can be decreased so as to obtain a greater mileage.

From the foregoing description, it will be seen that I have provided a carbureter with a main nozzle and an auxiliary air chamber 75 having a floating valve for controlling the communication between said auxiliary air chamber and mixing chamber; said valve being supported by a pivoted yoke through the medium of a spring; means being provided 80 for adjusting the position of the yoke so as to regulate the volume of air entering the mixing chamber, whereby the engine to which the carbureter is attached, can be used for braking the vehicle when coasting down 85 a hill.

The form of stop 26 as herein shown for limiting the movement of the crank, comprises a screw working in a threaded bore formed in a bracket extending from the casting of the carbureter, said bracket carrying a spring member coöperating with the head of the screw for holding the same in adjusted position, and it will be seen that by adjusting the stop, the position of the yoke within the 90 chamber can be changed so as to hold the floating valve off of its seat, the proper 95 distance.

While I have shown and described particular means for adjusting the position of 100 the yoke for supporting the floating valve, I do not wish to limit myself to any exact construction for accomplishing this result, as various other means can be employed without departing from the spirit of my invention.

In the drawings, I have shown the operating rod 23 connected to a stud pivotally mounted in the free end of the crank arm 22 in order to provide a pivotal connection between the rod and crank arm; but it is, of course, understood that other means can be employed for connecting the operating rod to the crank and that the operating rod can be connected in various ways through the medium of links and levers to a suitable manually operated member mounted upon the dash of the motor vehicle.

I claim:

1. A carbureter having a mixing chamber, a main air inlet extending into said mixing chamber, a fuel nozzle arranged within said air inlet, an auxiliary air chamber provided with air inlets, a floating valve for controlling communication between said auxiliary 120 air chamber and mixing chamber, and means for adjusting the relative position of said floating valve in respect to its seat.

2. In a carbureter, the combination with a floating suction-controlled valve, a nozzle 125

arranged under said valve, a pivoted member arranged in the path of travel of said suction-controlled valve for retarding the movement thereof, and a spring for floating said valve.

3. In a carbureter, the combination with the mixing chamber thereof, of a Venturi tube extending into said mixing chamber, a fuel nozzle arranged within said Venturi tube, an auxiliary air chamber, a floating valve slidably mounted upon said Venturi tube for controlling communication between said air chamber and mixing chamber, and means for adjusting the position of said floating valve in respect to its seat.

4. In a carbureter, the combination with a floating suction-controlled valve, a nozzle arranged under said valve, means for retarding the opening movement of said valve, and means for adjusting the relative position of said valve in respect to its seat.

5. A carbureter, having a main fuel nozzle and an auxiliary fuel nozzle, a floating valve arranged over the auxiliary fuel nozzle, means for retarding the upward movement thereof, and means for adjusting the position of said valve in respect to its seat.

6. A carbureter, having a mixing chamber, a Venturi tube extending into said chamber, an auxiliary air chamber surrounding said Venturi tube in a plane below said mixing chamber, a floating suction-controlled valve slidably mounted upon said Venturi tube for closing said air chamber, and means for adjusting the position of said suction-controlled valve in respect to its seat.

7. A carbureter, having a mixing chamber, a Venturi tube extending into said mixing chamber, a fuel nozzle arranged within said Venturi tube, an air chamber surrounding said Venturi tube below said mixing chamber, a high speed nozzle arranged in said air chamber; a suction-controlled valve arranged above and adjacent said speed nozzle for controlling communication between said mixing chamber and air chamber, means for retarding the opening movement of said suction-controlled valve, and manually operated means for adjusting the position of said suction-controlled valve in respect to its seat.

8. A carbureter, comprising a casing having a mixing chamber and main and auxiliary air inlets leading thereto, a valve for controlling the passage of air to the auxiliary air inlet, spring for floating said valve; and manually operated means for adjusting the position of said spring.

9. A carbureter, having an auxiliary air chamber provided with a high speed nozzle, a Venturi tube, a main fuel nozzle arranged within said Venturi tube, a suction-controlled valve for closing said auxiliary air chamber, and manually operated means for

supporting said suction-controlled valve in different positions above its seat.

10. A carbureter, having a main fuel nozzle, an air passage surrounding said nozzle, an auxiliary air chamber, a suction-controlled floating valve for closing said auxiliary air chamber, and a cam-operated member for supporting said suction-controlled valve in different positions in respect to its seat.

11. A carbureter, having a mixing chamber, a main fuel nozzle, and an air passage surrounding said nozzle and extending to said mixing chamber, an auxiliary air chamber having communication with said mixing chamber, a suction-controlled valve for controlling communication between said mixing chamber and air chamber, a spring for floating said valve; and manually operated means for adjustably supporting said spring for adjusting the position of said suction-controlled valve in respect to its seat.

12. A carbureter, having a mixing chamber, a Venturi tube extending into said chamber, an auxiliary air chamber having communication with said mixing chamber, a suction-controlled valve for controlling communication between said mixing chamber and air chamber, a spring arranged under said suction-controlled valve, a yoke for supporting said spring, and manually operated means for adjusting said yoke.

13. In a carbureter, the combination with a floating suction-controlled valve, of a spring for floating said valve, a yoke for supporting said spring; and means for adjusting the position of said yoke.

14. A carbureter, having a main fuel nozzle and an auxiliary fuel nozzle surrounded by air passages, a floating valve arranged over said auxiliary fuel nozzle, a spring for floating said valve, and adjustable means for supporting said spring.

15. A carbureter, comprising a casing having a mixing chamber and an air chamber, a floating valve for controlling communication between said air chamber and mixing chamber, a pivoted yoke, a flanged collar mounted upon said yoke, a spring carried by said collar for supporting said valve, a cam co-operating with said yoke, a shaft upon which said cam is mounted, and manually operated means for oscillating said shaft for adjusting the position of said yoke.

16. A carbureter, having a fuel chamber provided with a central air passage, an air chamber arranged upon said fuel chamber, a mixing chamber arranged above said air chamber, said air chamber having an opening communicating with said mixing chamber, a Venturi tube arranged within the air passage extending into said mixing chamber, a fuel nozzle arranged within said Venturi tube, a fuel nozzle arranged within said

- air chamber, a valve for closing the opening in said air chamber, means for retarding the opening movement of said valve, and manually operated means for adjusting the position of said valve in respect to said seat. 5
17. In a carbureter, the combination with a fuel chamber having a central air passage, of an auxiliary air chamber arranged within said fuel chamber, a Venturi tube arranged within said air passage extending through said auxiliary air chamber, a mixing chamber arranged within said auxiliary air chamber, a suction-controlled valve for controlling communication between said mixing chamber and auxiliary air chamber, a fuel nozzle arranged within said Venturi tube, and manually operated means for adjusting the relative position of said suction-controlled valve in respect to its seat. 10
18. A carbureter, having a mixing chamber and means for conveying air and fuel thereto, an auxiliary air chamber having communication with said mixing chamber, a valve for controlling communication between said mixing chamber and air chamber, a high speed nozzle arranged in said auxiliary air chamber adjacent said valve and means for adjusting the relative position of said valve in respect to its seat. 15
19. A carbureter, having a mixing chamber and an auxiliary air chamber communicating therewith, a valve for controlling communication between said mixing chamber and auxiliary air chamber, a pivoted yoke mounted in said air chamber, a flanged sleeve carried by said yoke, a spring carried by said sleeve for floating said valve, and means for adjusting the position of said yoke. 20
20. A carbureter, having a main fuel nozzle and means for conveying air thereto, an auxiliary air chamber, a valve for controlling the passage of air through said chamber, means for floating said valve; means for retarding the opening movement of said valve, and means for adjusting said floating means for adjusting the position of said valve in respect to its seat. 25
21. A carbureter, having a main fuel nozzle and means for conveying air thereto, an auxiliary air chamber, a valve for controlling the passage of air through said chamber, a high speed nozzle arranged within said auxiliary air chamber under said valve, means for retarding the opening movement of said valve; and means for adjusting said floating means for adjusting the position of said valve in respect to its seat. 30
22. A carbureter, having a Venturi tube surrounded by an auxiliary air chamber, a floating valve slidably mounted upon said tube controlling the passage of air through said auxiliary chamber, a pivoted yoke mounted in said chamber, a spring carried by said yoke for supporting said valve, and means for adjusting the position of said yoke within said chamber. 35
